(57) **CLAIM**

I claim the ornamental design for a watch bracelet portion, as shown and described.

DESCRIPTION

FIG. 1 is a perspective view illustrating the top, front and left side of a design of the watch bracelet portion;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The broken-line disclosure in the above referenced figures illustrate an example intended environment for illustrative purposes only and forms no part of the claimed design.
